UNITED STATES PATENT OFFICE

152,750

DESIGN FOR AN UNDERSHOE

Harry Shapiro, Augusta, Ga.

Application October 29, 1948, Serial No. 149,379

Term of patent 14 years

(Cl. D7—7)

To all whom it may concern:

Be it known that I, Harry Shapiro, a citizen of the United States, residing at Augusta, county of Richmond, State of Georgia, have invented a new, original, and ornamental Design for an Undershoe, of which the following is a specification, reference being had to the accompanying drawing, forming a part thereof and wherein:

I claim:

The ornamental design for an undershoe, substantially as shown.

HARRY SHAPIRO.
